UNITED STATES PATENT OFFICE.

JOHN E. HILL, OF WEST SOMERVILLE, MASSACHUSETTS, ASSIGNOR OF ONE-HALF TO
JOHN M. CUMMINGS, OF STONEHAM, MASSACHUSETTS.

AUTOMOBILE SIGNAL.

Application filed August 2, 1921. Serial No. 489,159.

To all whom it may concern:

Be it known that I, JOHN E. HILL, a citizen of the United States, residing at West Somerville, county of Middlesex, State of 5 Massachusetts, have invented an Improvement in Automobile Signals, of which the following description, in connection with the accompanying drawing, is a specification, like characters on the drawing representing 10 like parts.

This invention relates to automobile signals of the type comprising a plurality of swinging signal arms which are normally confined within a housing that is attached to 15 the windshield post or some other suitable part of the automobile, but which can be swung out of the housing into display position by the operator of the automobile, thereby giving a signal as to the intended movements of the operator.

One object of my invention is to provide a novel automobile signal of this type which is simple in construction and which can be inexpensively manufactured, and which has 25 the further advantage that it is easy to operate.

In order to give an understanding of my invention, I have illustrated in the drawings a selected embodiment thereof, which will 30 now be described, after which the novel features will be pointed out in the appended claim.

In the drawings, Fig. 1 is a perspective view of a portion of an automobile having 35 my improvements applied thereto.

Fig. 2 is a perspective view of the signal device.

Fig. 3 is a vertical sectional view on substantially the line 3—3, Fig. 4.

40 Fig. 4 is a vertical sectional view on substantially the line 4—4, Fig. 3.

My improved signal comprises a box or housing 1, which is open at one side as shown at 2, and which is constructed to receive a plurality of signal arms 3, 4 and 5, which are pivotally mounted at the lower portion of the housing, so that they may be swung from their vertical position within the housing into a horizontal display position. 45 These signal arms will preferably be of different colors and I find it will be convenient to have one signal arm a red color, one a green color and the other a white color, although I desire to state that the colors of 50 the arms may be varied as desired.

The signal arm 3 is shown as fast on a shaft 6, which is journaled at one end in one wall of the housing, as shown at 7, and the other end of which extends through the opposite wall of the housing, and is provided with a knob or hand wheel 8 by which the shaft may be turned. Since the signal arm 3 is fast on the shaft, said arm may be swung from its vertical concealed position into its horizontal display position by simply turning the knob 8 in the right direction.

The signal arm 4 is fast on a sleeve 9, through which the shaft 6 extends, said shaft forming a bearing for the sleeve. This sleeve 9 extends through one wall of the housing and is provided with a hand wheel 10 on its end, by which it and the signal 4 may be turned.

The signal arm 5 is rigid with another sleeve 11, which also extends through the side of the housing, and has fast thereon a hand wheel 12, by which it may be turned. The sleeve 11 is shown as supported by a suitable bearing 13, said bearing being of sufficient extent to properly support the sleeve. The sleeve 9 is supported by the sleeve 11, and the shaft 6 is supported by the sleeve 9.

The hand wheels 8, 10 and 12 are in axial alignment, and I will preferably make the hand wheel 12 larger than the hand wheel 10, and the hand wheel 10 larger than the hand wheel 8.

The housing 1 is adapted to be secured to the wind-shield post 14 of an automobile 15, or may be attached to the side of the automobile by any suitable means. I prefer, however, to secure it to the wind-shield post, and this may be done by providing the housing with suitable clamping device 16 adapted to embrace the wind-shield post 14.

The hand wheels 8, 10 and 12 project from the side of the housing 1, which faces the driver of the automobile when the housing is attached to the wind-shield post. Said hand wheels are located within convenient reach of the driver. Since the hand wheels 8, 10 and 12 are of different sizes, it will be easy for the driver to manipulate any one of the hand wheels without disturbing the other hand wheel, and therefore any one of the signal arms can be readily moved down into horizontal display position by simply giving the proper hand wheel a quarter turn anti-clockwise.

In order to retain the signal arms in their elevated concealed position, I have provided the plurality of resilient arms 17, which are secured to the inside of the housing and are 5 adapted to frictionally engage the tops of the arms when they are in vertical position, as clearly seen in Fig. 4. These resilient arms are bent slightly at their ends so that they partially embrace the ends of the 10 signal arms, but because of their yielding character, they will readily give to allow the signal arms to be swung from vertical to horizontal position, or vice versa. The three signal arms may be used individually to give 15 a "Turning-to-the-left" signal, a "Turning-to-the-right" signal, and also a "Stop" signal.

It is sometimes desirable to give some signal in addition to the three above mentioned 20 signals, such for instance as a "Backing-up" signal, or a "Starting" signal. I have provided for giving these added signals by so constructing my signal device that when two or more of the signal arms are swung down 25 into display position, both arms will be visible, thus making a two-color signal. With the three signal arms of different colors, it is possible to make three different two-color signals. These two-color signals are provided for by making the housing with the stop 30 device for the signal arms, which holds the arms at different angles when they are in display position. This stop device is shown as a block 18 secured within the housing, and 35 provided with supporting portions 19, 20 and 21 for the three signal arms. These supporting portions are at different elevations so that these signal arms will occupy different angles

in their display positions, the signal arm 3 being supported slightly above the other two 40 signal arms and the signal arm 4 being supported slightly above the signal arm 5. This is clearly shown in dotted lines in Figs. 2 and 4, and these figures illustrate the manner in which two-color signals may be given. 45

My invention is very simple in construction, can be inexpensively manufactured, is easy to install on an automobile, and is extremely easy to operate.

I claim:

In an automobile signal, the combination with a housing adapted to be secured to an automobile, of a shaft journalled in said housing near its lower end and projecting beyond the same, a signal arm fast on said shaft, a sleeve surrounding said shaft and also projecting beyond the housing, a second signal arm fast on said sleeve, a second sleeve surrounding the first named sleeve and also projecting beyond the housing, a third signal arm fast on said second sleeve, said shaft and said sleeves each having a hand wheel fast on the projecting portion thereof, by which the signal arms may be swung from a vertical concealed position downwardly into a horizontal display position, said signal arms having different colors, and a stepped rest for said signal arms when in display position, which is constructed to hold each arm at a slightly different angle from the other signal arms whereby two-color signals may be given.

In testimony whereof, I have signed my name to this specification.

JOHN E. HILL
